GARMENT

Louis Mintzes, Brooklyn, N. Y.

Application February 20, 1940, Serial No. 319,899

2 Claims. (Cl. 2—79)

This invention relates to garments and particularly to a convertible sport costume and gymnasium suit.

The main object of the invention is to provide a garment of this character which includes a waist and skirt portion, and which enables the free use of the limbs during athletic exercises.

Another object of this invention is to provide a costume of this character which embodies a divided skirt and which is equipped with means for readily converting the athletic suit into a street costume.

Another object of this invention is to provide a convertible garment having a bifurcated skirt providing leg portions loosely inclosing the legs of the wearer and having inverted pleat elements at the front and rear for covering the said bifurcated front and rear so as to simulate a continuous skirt hem.

Another object of this invention is to provide insert members in the said bifurcations for closing said openings against drafts, the said insert members comprising leg embracing members and the said insert members bridging the space between the lower edge of the said bifurcations and the leg embracing members.

Another object of this invention is to secure said inserts to said bifurcations by stitching the top edge portions of said inserts to the top portion of the bottom hem, so as to permit the bottom edge portion of the garment to overhang and to provide a sharply defined linear edging and to also permit the said inserts to be extensible below the said hem.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the convertible garment, the front inverted pleat covering the opening between the bifurcated leg inclosing members to simulate a skirt.

Figure 2 is a rear elevation of the convertible garment, the rear inverted pleat covering the opening between the bifurcated leg inclosing members to simulate a skirt, and showing the leg inclosing members in a position of concealment under the overlying outer fabric.

Figure 3 is an enlarged cross-sectional view 55

taken in the directions of the arrows along the line 3—3, shown in Figure 1 and slightly above the crotch.

Figure 4 is an elevational view of the two front panels and two side sections ready for sewing together.

Figure 5 is an enlarged fragmentary lower portion of the garment, partly in cross-section, and with the inserts in exposed position.

Figure 6 is an enlarged cross-sectional view, the section being taken as on line 6—6 in Figure 2.

Figure 7 is a perspective view of a fragmentary portion of one of the leg enclosing members of the garment and showing a detachable insert.

In the illustrated embodiment of the invention the numeral 10 indicates a convertible garment comprising an upper body portion 11 and a lower skirt portion 12. The skirt portion flares outwardly from the waistline to the bottom. The skirt portion has been bifurcated to form leg portions or leg enclosing members 13, 13, loosely inclosing the legs of the wearer. The two leg portions have been joined along a seam 14 extending from the bottom edge 15 of the garment upwardly along the full length of the crotch 16.

In order to make this garment convertible from a gymnasium suit to a form-fitting sport costume, I have formed an inverted front pleat 17 and an inverted rear pleat 18, both of said pleats being positioned at the center portion of the garment. The pleats 17 and 18 are stitched down.

As shown in Figure 3, the meeting edges of the pleats 17 and 18 are aligned in substantially abutting relation so as to provide a sharply defined linear edging all around the bottom edge of the garment.

Referring to Figure 4, it will be noted that the garment herein disclosed is sectional, that is, it is built up of two front panels 19, 19, and two side sections 20, 20, forming the front portion of the garment 10. The rear portion of the garment is built up of two panels and two side sections similar to the panels 19 and side sections 20. It will be noted that the waist portions 21 of the side sections 20 and the waist portions 21' of the panels 19 have been made narrower than the neck and bottom hem portions so as to make the garment form-fitting.

The front panels 19 have been cut so as to permit folding along the dot-and-dash line 22 for the formation of the inverted pleat 17, shown in Figure 3. The lower ends of the front panels 19 have been formed with sideways extensions 23

forming portions of the leg inclosing members 13, shown in Figure 3.

As shown in Figures 1, 2, and 3, the front and rear invert pleat elements are substantially in abutting relation at the center of the garment and cover the bifurcated leg inclosing members 13.

As shown in Figure 2, the elements of the rear invert pleat 18 have been joined at a point 24, at the waist line and at a point 25 below the neck so as to permit distension of the waist and bust portion of the garment 10 during gymnastic drills or other forms of athletics. This distension is possible due to the opening up of the rear invert pleat.

To prevent exposure of the body during athletic activities, I have provided inserts or leg embracing members 26 located at a predetermined position within the leg inclosing members 13 and arranged to closely encircle the limbs of the wearer and to close the annular spaces between the leg inclosing members 13 and the limbs of the wearer.

Each insert 26 comprises a converging body 27 and a cuff 28. The body 27 is made of a fabric which is very pliable. The cuff 28 is made of a fabric which has a relatively high inherent elasticity such as knit fabric. The cuff 28 is attached to the body 27 along an edge thereof under tension so that when the tension is relieved and the cuff resumes its normal position the body 27 will be gathered along said edge. The cuffs 28 are dimensioned so as to grip the limbs of the wearer. The inserts 26 present a converging form in their normal operating positions.

In practice, the upper edges of the bodies 27 are attached by circumferential stitching 29 to the leg members 13 interiorly thereof at the top portion 30 of the bottom hem 31, each insert 26 being of sufficient length to extend below the bottom of the leg enclosing members 13.

When the garment is being worn, the calves of the wearer will be encircled by the inserts 26 and will be closely gripped by the elastic cuffs 28 to provide protection against drafts and colds and permit the garment to be worn under all weather conditions. The construction of the flexible inserts as above described permits the garment to hang in the same way as if the inserts were not present.

It is to be noted that the importance of attaching the inserts 26 to the top portion 30 of the hem 31 lies in the fact that whether the inserts are below or above the line of attachment 29, the bottom edge or lower border line 15 of the garment remains at all times clearly defined and hangs in an unhampered and free condition. The graceful form-fitting lines of the garment are thus not destroyed. As best shown in Figure 5, it will be seen that the bottom edge 15 of the leg enclosing members terminates slightly below the crotch 16.

As shown in Figures 1, 2 and 4, one of the objects of this invention is to provide a convertible form-fitting garment in which the panels and side sections are integral from the neck down to the bottom edge or hem 31. This makes possible the construction of a garment without any cross-seams at the waist and which does away with the use of a belt, while retaining its form-fitting qualities and producing a slenderizing effect.

As shown in Figure 6, the distended position at the rear of the waist portion 32 of the garment 10 is shown by the dot-and-dash line 33. This

action-back construction makes it possible for the wearer during athletic exercises to distend the waist and bust portion of the garment between the points 24 and 25.

For the purposes of this invention which are to provide a garment which can be quickly changed for different uses in athletics, I have provided a convertible collar 36 which can be transformed into a hood 37 for covering the head of the wearer, as is well known in the art.

In the assembled position shown in Figure 1, the elements of the front invert pleat 17 are connected by suitable releasable closure means such as by means of buttons 51 and buttonholes 52, shown in Figure 6.

Figure 7 shows an enlarged fragmentary portion of a modified tubular insert 26' which may be detachably secured to the hem 31 of the leg portion 13 of the garment. As shown, the hem 31 has been raised up to show a braid 55, secured by a line of stitching 56. The braid 55 comprises spaced loops 57. The modified tubular insert 26' comprises a flexible fabric 27', having a hem 58 at its upper elevation. A braid 59 having spaced loops 60 has been secured to the hem 58 by stitching 62. A cord 61 has been interwound with the loops 57 and 60 so that the said loops will come into registry when the cord has been drawn taut around the upper portion of the insert 26'.

While I have shown one form of detachable means in Figure 7 for securing the removable leg embracing inserts to the garment, it is to be understood that I may employ any other means for detachably securing the inserts to the garment, such as slide closure means of the "Zipper" type.

In accordance with the patent statutes I have described and illustrated the preferred embodiment of my invention, but it will be understood that various changes and modifications can be made therein without departing from the spirit of the invention as defined by the appended claims.

I claim:

1. A garment comprising a bifurcated sport costume and gymnasium suit, said garment comprising front and rear portions extending from the neck to the vicinity of the knees of the wearer, said portions below the crotch having inner extensions connected together forming individual leg enclosing members including a hem, the front and rear portions having folds providing inverted pleats at the center of the front and back of the garment, the inverted pleat elements below said crotch at the front and back meeting each other and covering the opening between the said individual bifurcated leg enclosing members, said individual leg enclosing members terminating in conical leg embracing members, said leg embracing members being secured to said leg enclosing members at the top portion of the said bottom hem, said leg embracing members being of sufficient length to permit movement thereof below the bottom of said leg enclosing members to convert said sport costume into a gymnasium suit, said leg embracing members being adapted to be moved upwardly into a position of concealment under the overlying outer fabric.

2. A garment comprising a bifurcated sport costume and gymnasium suit, said garment comprising front and rear panels extending from the neck to the vicinity of the knees of the wearer, said panels below the crotch having inner extensions connected together forming individual leg

enclosing members including a hem, the front and rear panels being folded to provide inverted pleats at the center of the front and back of the garment, said inverted front pleat having releasable closing means, the inverted pleat elements below said crotch at the front and back meeting each other and covering the opening between the said individual bifurcated leg enclosing members, said individual leg enclosing members terminating in conical leg embracing members, said leg 10

embracing members being secured to said leg enclosing members at the top portion of the said bottom hems, said leg embracing members being of sufficient length to permit movement thereof below the bottom of said leg enclosing members to convert said sport costume into a gymnasium suit, said leg embracing members being adapted to be moved upwardly into a position of concealment under the overlying outer fabric.

LOUIS MINTZES.
